TYPEWRITING MACHINE

Charles H. Beiderbecke, Rochester, N. Y., assignor
to International Business Machines Corpora-
tion, New York, N. Y., a corporation of New
York

Application July 27, 1937, Serial No. 155,854

11 Claims. (Cl. 197—126)

This invention relates to typewriting machines particularly fan folded or continuous billing machines, and is an improvement in the machine disclosed in application Serial No. 127,684, filed 5 February 25, 1937 by C. H. Beiderbecke.

The broad object of the present invention is to provide novel means to hold the carbon stripping carriage in retracted position.

An object is to provide automatic latching 10 mechanism which is rendered effective when the platen is raised preparatory to straightening the forms for the purpose of shifting the carbon sheets to the next set of forms.

Another object is to provide a latching mechanism 15 for the carbon stripper carriage which is controlled by the raising and lowering of the platen.

An object is to provide a latching mechanism which is normally ineffective to hold the carbon 20 stripper carriage in retracted position but which is rendered effective when the platen is raised and is automatically disabled when the platen is returned to writing position.

Further objects of the instant invention reside 25 in any novel feature of construction or operation or novel combination of parts present in the embodiment of the invention described and shown in the accompanying drawings whether within or without the scope of the appended claims and 30 irrespective of other specific statements as to the scope of the invention contained herein.

In the drawings:

Fig. 1 is a plan view showing the forms carrier and a portion of the typewriting machine; 35 Fig. 2 is an enlarged plan view of the carbon stripper carriage;

Fig. 3 is a left side elevation on a large scale of the typewriter carriage;

Fig. 4 is a vertical section on the line 4—4 in 40 Fig. 1.

The present invention, for convenience in description, is illustrated in the drawings as applied to the fan fold billing machine disclosed in the above application. However, it will be 45 understood that it is not limited to the specific form of machine shown but may be applied to other fan fold billing machines equally as well. Since the machine described in the above application is now well known in the art, it will not 50 be described in detail, but a very brief description will be given herein of the construction and operation of the machine.

The numeral 10 in Figs. 1 and 3 designates generally the typewriting machine which may be the 55 well known "International" electric writing ma-

chine, formerly known as the "Electromatic". The carriage is generally designated 11 and is mounted in a well known way upon grooved rails 12. Pivoted upon extension plates 13 secured to the carriage end plates are arms 14 which at their forward ends rotatably support the platen 15. Normally, the platen is latched in writing position by means of two latches 16 pivotally mounted on the arms 14, which latches 16 engage lugs 17a formed in adjustable brackets 17 secured to the end plates of the carriage. The latches 16 are released to raise the platen by means of a hand lever 18 having a pin 18a engaging one of the latches whereby the initial lifting movement upon the hand lever 18 first 10 releases both latches 16 and thereafter rocks the arms 14 on their pivots 14a. When the platen is in fully elevated position the arms 14 abut stop lugs 13a on the extension plates 13. Only one hand lever 18 is provided which is located at the 20 left hand end of the carriage and the latches 16 are both secured to a rod 16a journaled in arms 14 whereby both latches are released simultaneously when the lever 18 is raised by hand. The platen 15 is held in elevated position partly 25 by its own weight and partly by counter-balancing springs 19 which are hooked around the edges of the arms 14 and the edges of tension spring 13, respectively.

Adjustably secured to the base of the typewriter at 20 (Fig. 1) is a framework 21 made of tubing. This framework supports a rail 22 on which is movably mounted the forms carrier. The forms carrier includes a plate 23 which is removably secured to the platen by means of a 35 bracket 24 and the rod 25 mounted in extension plates 13. The plate 23 is slidably mounted on a rod 22 by means of rollers 26 (Figs. 1 and 2) on a bracket 27 secured to the underside of the plate 23 whereby the plate 23 travels with the carriage. The plate 23 has its longitudinal edges bent upwardly and outwardly to provide divergent flanges 23a which act as tracks to guide the ribbon stripper carriage 28 for movement toward and away from the platen 15. 40

The carbon stripper carriage 28 (Fig. 2) comprises a flat plate on which is mounted grooved rollers 29 engaging the flanges 23a. The right hand pair of rollers 29 is mounted on a truck 30 which has a pivoted and sliding movement 50 with reference to a stud 31 carried by the carriage 28 which truck is actuated by means of a spring 32 to cause the right hand pair of rollers 29 to engage the right hand flange 23a. A bar 33 is removably mounted upon the carbon stripper 55

carriage 28 and has secured thereto posts 34 which project through slots 35a in the carbon sheet anchoring blades 36.

For the purpose of retracting the carbon stripper per carriage 28, there is provided a coil spring 37 (Figs. 1 and 2). This spring is anchored to a pin 39 on the carbon stripper carriage and extends rearwardly, around a pulley 40 on a stud 41 mounted on the top surface of the rear end of the plate 23, and forwardly, parallel with the right hand flange 23a, and is anchored at the forward end of the plate 23. Thus the spring 37 normally has a tendency to draw the carbon stripper carriage rearwardly away from the platen, that is, to the right in Fig. 1.

As the typing of a set of forms with interleaved carbons proceeds, the operation of line spacing the forms wrapped around the platen causes the forms, the carbon stripper carriage 28, and the carbons anchored thereto to be drawn forwardly, that is, toward the platen 15 thereby progressively tensioning the spring 37. When the typing of a set of forms is completed, it is necessary to shift the carbons from the completed set of forms to the forms immediately following. For this purpose, the platen is raised by means of hand lever 18 which releases the forms permitting spring 37 to retract the carbon stripper carriage. Naturally the forms and carbon sheets are also retracted.

The present invention contemplates that the stripping operation shall take place after the spring 37 has retracted the carriage 28 until it strikes an adjustable stop and contemplates the provision of a latch which is rendered potentially effective, when the platen is raised, to latch the carriage 28 in retracted position. In order to limit the retracting movement of the carbon stripper carriage 28, there is provided a stop 42, best shown in Figs. 2 and 4, consisting of a hub to which is secured a member 43 having a resilient cushion 44 in the plane of the plate comprising the carriage 28. The hub 42 is provided with a thumb screw 45 which engages a flat formed in the top of the rod 46 supporting said hub. The rod 46 is mounted on the top surface of the plate 23 and extends parallel with flanges 23a.

The member 43 has an offset lug 47 which cooperates with a spring actuated latch member 48 pivotally mounted at 49 on a bracket 50 secured to the carbon stripper carriage 28. The latch 48 is urged in a clockwise direction by means of a spring 51 hooked into a hole in the latch and engaging the underside of a plate 28. The latch 48 is provided with an offset lug 52 adapted to ride on the top surface of a bar 53 which is angular in section and is pivoted at 54 (Fig. 1) to front and rear ends of the plate 23. It will be seen that when the carbon stripper carriage 28 is retracted, the lug 52 will ride along top surface of bar 53 adjacent the left hand edge thereof (Fig. 2) until ultimately the latch snaps over the lug 47 as in Fig. 4. Normally, however, the latch 48 is held in elevated position to prevent latching engagement thereof with lug 47 and this is accomplished by means of bar 53 through connections to the platen raising mechanism.

Pivottally mounted on a stud 55 (Figs. 1 and 3), carried by a bracket 56 secured to the underside of the plate 23, is a bell crank 57 one arm of which extends horizontally to a point just in the rear of the left hand platen supporting arm 14. The lever 57 is operated by a spring 58 so as to

be held in engagement with the right hand lug formed in the bracket 24 by means of which plate 23 is mounted on the rod 25. In this position, lever 57 is engageable by the right hand platen supporting arm 14 so as to be rocked slightly clockwise (Fig. 1) whenever the platen is raised and arms 14 are brought against the stop lugs 18a. The other arm of the lever 57 extends substantially parallel with bar 53. Adjacent the end of the rearwardly extending arm of lever 57, the bar 53 is provided with a downwardly extending arm 59 (Fig. 3) formed in a bracket secured to the bar 53. The arm 59 and the lever 57 are interconnected flexibly by means of a spring 60 which is hooked in a hole formed in the bracket 59 and is also hooked around the rearwardly extending arm of lever 57.

Normally, when the platen is in lowered position, the spring 58 holding arm 57 against the lug formed on bracket 24 also holds the left hand edge of the bar 53 (Fig. 2) in elevated position thereby preventing engagement of the latch 48 with the lug 47 of the stop 42. When the platen is raised preparatory to retracting the pack of forms with interleaved carbons, the left hand arm 14 engages the lever 57 and rocks it clockwise (Fig. 1) thereby, through the spring 60, rocking the bar 53 in a direction to depress the left hand edge thereof. This causes the latch 48 to move downwardly to a position to permit the said latch to engage the lug 47 when the spring 37 draws the carriage 28 against the stop 42, thereby latching the carriage 28 in its retracted position. The leading edges of the forms may now be grasped and pulled forwardly into engagement with the usual leading edge gage 61 which is adjustably mounted on rod 62 fixed to the framework of the typewriter.

Since the carbon carriage is rigidly held while the forms are being drawn forwardly, a relative shifting movement will occur between the carbon sheets and forms whereby the carbon sheets are shifted to the next set of forms. The platen may now be lowered and the typed forms severed from the succeeding set of forms by means of the tearing knife usually provided for that purpose.

During the initial part of the movement of the platen to typing position, the spring 58 will rock the lever 57 in a counterclockwise direction (Fig. 1) thereby elevating the left hand edge (Fig. 2) of the bar 53. This lifts the latch 48 out of engagement with the lug 47 and thereby frees the carbon stripper carriage for movement toward the platen when the typing of the next set of forms takes place.

While there has been shown and described and pointed out the fundamental novel features of the invention as applied to a single embodiment it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a continuous billing machine, the combination with the carriage of the typewriting machine; a forms carrier attached to said carriage and movable therewith, said forms carrier including a retractable carbon stripper carriage; latching mechanism for holding the carbon stripper carriage in retracted position, a platen displace-

ably mounted on the typewriter carriage so as to be movable from a typing to a non-typing position, and means operative upon the displacement of the platen for rendering said latching means effective.

5 2. In a continuous billing machine, the combination with the carriage of the typewriting machine, a platen movably mounted in said carriage so as to be displaceable from a typing to a non-typing position, a forms carrier connected to said carrier so as to be movable therewith and including a reciprocatory carbon stripper carriage, a stop for limiting reciprocatory movement of said carbon stripper carriage away from the platen, latching mechanism for holding the carbon stripper carriage against said stop, and means responsive to movement of the platen from its typing to non-typing position for rendering the latch effective.

20 3. In a continuous billing machine, the combination with the carriage of the typewriting machine, of a platen, platen displacing mechanism for moving the platen from a typing to a non-typing position whereby to permit straightening forms wrapped around the platen, a forms carrier connected to said carriage so as to be movable therewith and including a carbon stripper carriage movable toward and away from the platen, said carbon stripper carriage having 25 means to anchor carbon strips interleaved with said forms, an adjustable stop for limiting movement of the carbon stripper carriage away from the platen; means operative when the platen is raised to automatically draw the carbon stripper carriage, the forms and carbon strips supported thereby rearwardly of the platen so as to bring said carbon carriage against said stop, a latch adapted to hold the carbon stripper carriage against said stop, a release bar extending from 30 said latching mechanism to a point in rear of the platen, said release bar when operated disengaging said latch permitting forward movement of the carbon stripper carriage, and means controlled by the platen raising mechanism for operating said release bar when the platen is moved to typing position.

4. In a machine of the class described, the combination with the carriage of the typewriting machine, of a platen, means for displacing the platen from a typing to a non-typing position, a reciprocable carbon stripper carriage movable toward and away from the platen, means to limit movement of said carbon stripper carriage away from the platen, means for automatically retracting said carbon stripper carriage when the platen is displaced, a latch for holding the carbon stripper carriage in retracted position, and means responsive to movement of the platen displacing mechanism for releasing said latch.

60 5. In a machine of the class described, the combination with the carriage of the typewriting machine, of a platen, means for movably mounting the platen on said carriage for displacement from a typing to a non-typing position, a carbon strip anchoring device movable toward and away from said platen, means operative upon a displacement of the platen to non-typing position for moving the carbon strip anchoring device away from said platen, means for holding said device in its retracted position to permit a relative shifting movement between forms and the carbon strips interleaved with the forms and anchored to said device, and means operative upon a movement of the platen to its typing position 65 for releasing said latch.

6. In a machine of the class described, the combination with the carriage of the typewriting machine, of a platen, means for displacing the platen from a typing to a non-typing position to permit straightening of forms wrapped around the platen, a supporting frame mounted in the rear of the typewriter, a track connected to the typewriter carriage and movably supported by said frame so as to travel with said carriage, a carbon stripper carriage movably mounted on said track 10 so as to be reciprocable toward and away from the platen, latching means adjustably mounted along said track and including a stop for limiting retracting movement of the carbon stripper carriage, a latch operating bar cooperating with said 15 latch and extending parallel with said track to a point adjacent the carriage of the typewriter, and connections between the platen displacing mechanism and said bar for operating the latter to release the latch when the platen displacing 20 mechanism is operated.

7. In a machine of the class described, the combination with the carriage of the typewriting machine, of a platen displaceably mounted in said carriage for movement from a typing to a non-typing position, a device for supporting one 25 end of a carbon strip and movable toward and away from the platen, means to hold said device in retracted position, and means operative to release the holding means when the platen is moved 30 to typing position.

8. In a machine of the class described, the combination with the carriage of the typewriting machine, a platen mounted in said carriage for displacement from a typing to a non-typing position, a carriage movable toward and from the platen, said carriage having means to anchor carbon strips interleaved with forms wrapped around the platen, means for limiting movement of the carbon strip carriage in a direction away 35 from the platen, a spring for retracting said carbon strip carriage when the platen is displaced to non-typing position, means to hold said carbon strip carriage in the position determined by the limiting means, and connections between said 40 latch and the carriage of the typewriter whereby said latch is released by displacement of the platen.

9. In a continuous billing machine, the combination with the carriage of the typewriter, a carrier for continuous forms movable with the carriage; said carrier including a retractable member movable transversely of the line of travel of the typewriter carriage, on which member the continuous forms are supported, with means to attach a strip impregnated with transfer material to said member; means for holding said member in a retracted position, a platen movably mounted on the typewriter carriage so as to be displaceable to and from a typing position, and means operative upon a displacement of the platen in one direction for rendering the holding means effective and upon displacement in the other direction to render the holding means ineffective.

60 10. In a continuous billing machine, the combination with the carriage of the typewriting machine, a platen mounted on said carriage for displacement to and from a typing position, a forms carrier device mounted rearwardly of the carriage and including a carbon sheet anchoring device movable toward and away from the platen, means to limit reciprocatory movement of the carbon sheet anchoring device in a direction away 70 from the platen, means for holding the carbon 75

sheet anchoring device against said limiting means, and means responsive to displacement of the platen for rendering the holding means effective.

5 11. In a continuous billing machine, the combination with the carriage of the typewriting machine, a platen, means for movably mounting the platen on the carriage for displacement to and from a typing position, a form supporting device for continuous forms mounted rearwardly of the carriage and including a transfer sheet

operating member movable toward and away from the platen, means to limit said member in its movement away from the platen, means for automatically moving said member away from the platen when the platen is moved to a non-typing position, means to hold said member at the limit of its travel away from the platen, and means responsive to movement of the platen displacing mechanism for releasing the holding means.
